UNITED STATES PATENT OFFICE.

LE VERT CLARK, OF DETROIT, MICHIGAN.

REINFORCED COLLAPSIBLE TUBE.

1,109,110.

Specification of Letters Patent.

Patented Sept. 1, 1914.

Application filed June 18, 1913. Serial No. 774,320.

To all whom it may concern:

Be it known that I, LE VERT CLARK, a citizen of the United States, residing at Detroit, county of Wayne, State of Michigan, have invented a certain new and useful Reinforced Collapsible Tube, and declare the following to be a full, clear, and exact description of the same, such as will enable others skilled in the art to which it pertains to make and use the same, reference being had to the accompanying drawings, which form a part of this specification.

This invention relates to collapsible tubes. Its object is to combine a tube, of that character only, with a sufficiently rigid reinforcing member or bar, placed inside, to prevent the tubular portion from collapsing longitudinally; but allowing it to be freely collapsed transversely; by either flattening it against, or twisting it around, the bar; while expelling the contents of the tube.

Another object is to prevent the tube bursting while in use: which is more liable to happen when not reinforced. It becomes an unwieldy disagreeable article to deal with if crumpled up endwise, into a shapeless, unsanitary, mass, as is done by some in the use of ordinary devices; because the contents then exudes through broken places, while yet a large portion is still unused and has to be thrown away.

A further object is to impart to it, an axial or lengthwise rigidity as a new feature in a collapsible tube; so it cannot be rolled up endwise by a key or otherwise, into the short, clumsy package described. The reinforced tube may thus be more easily used in transferring a part of its contents to a brush held in the other hand; or used like a brush, with the handle always of the same length, in applying paste, soap, artist's paint, glue or other viscous materials to suitable objects; until the contents is all gone, without dirt or waste. The new and useful functions or advantages herein described, being practically impossible in an un-reinforced collapsible-tube container; which doubles up, because it has no backbone, or bends out of axial line, under extremely light stress of leverage; having no rigidity, unless modified as described, it soon becomes unmanageable. The old style container tube is therefore of very little service as a spreader or applier, after only a small portion of the contents has been used: as it also requires both hands to manipulate it successfully, at a time one hand

is required to hold the brush or other article, always used in connection with the tube. And lastly, its object is to make a new article of manufacture, of so much greater convenience and popularity, for the purposes intended, that it may induce more people to make better use of the sanitary and other preparations, of a viscous nature, now to be had, for which a tube is good only as a container; whereas the new reinforced collapsible tube is the best form, both of container and dispenser. When the corners or wings of the collapsed end are folded back the package is made relatively narrower in that dimension, by reason of which it may be gotten into a smaller box or carton.

In the drawings:—Figure 1 is a longitudinal horizontal section and plan view partly broken away, of the reinforced collapsible tube, embodying this invention. Fig. 2 is a longitudinal vertical section of the tubular portion of Fig. 1; and edge or side view of a flat reinforcing bar member, inside, in combination therewith. Fig. 3 is a cross-section, on the dotted line 3—3 of Fig. 2. Fig. 4 is a perspective view of a square edged reinforcing bar; a detail of Figs. 1 to 3. Fig. 5 is a slight modification showing a side view of a rounded reinforcing metal bar; a portion of it being looped, or broadened, inside the sealed end of the tube. Fig. 6 is a cross-section on the dotted line 6—6 of Fig. 5. Fig. 7 is a fragmentary top view of a detail of Fig. 4. Fig. 8 is a fragmentary view of a detail of Fig. 5.

The bar A (or B) is placed inside of the collapsible body portion of the tube 10; which latter is crimped or folded over itself to a limited extent to seal its filling end 11, after the viscous material and reinforcing bar are placed in the tube. The tube may also have a strip or cap, (not shown) crimped over the sealed end in the usual way for additional security against leakage. The tube may be made of tin, lead or other metal, paper or any suitable material easily and sufficiently collapsible; and the bar, of wood, metal, or other material of a suitable nature and rigidity; both members being made of proper size and shape for the purposes described. The tube may then be twisted or flattened as at 14 in Fig. 2, but preferably twisted if the bar is round, as at 15 in Fig. 5, to expel the contents.

12 is the discharge end; which may have the ordinary screw cap and nozzle 13 with an aperture 16 therethrough; or the end may be closed in any suitable manner.

5 In Figs. 1 to 4, inclusive, the reinforcing bar is shown to have a flat side C and end E and a relatively thin edge D. Its corners O (Fig. 7) at the filling or sealed end of the tube may be beveled off as shown at D'; or 10 left square, as extended by the dotted lines O. When this bar is placed inside, then the sealed end 11 of the tube may have its awkward corners Z again folded back on itself and the end E of the bar, nearly 15 incident with the corners O or the beveled corners D', inside. But the corners Z may be left square, as dotted in Fig. 1, without refolding as described.

20 In operation, the wall 10 may be flatly compressed against the bar A; beginning near the sealed end 11 and continuing past the portion 14 to the end 12 of Fig. 2; which causes the material to slowly exude through the orifice 16, as needed. However the presence of the bar makes it safe in inexperienced hands to collapse the device, without 25 observing the special care necessary with ordinary tubes; which latter to save the container walls, should be collapsed first near the sealed end; and if not done according to the usual printed directions, is followed by the disappointing results hereinbefore described. No printed directions for the manner of its use being necessary for a reinforced tube; such directions being overlooked or soon forgotten.

In the modification shown in Fig. 5, the reinforcing bar B may be square edge or 40 cylindrical; with one end broadened out, preferably by the loop B' of Fig. 8. Likewise the jagged corner Z' may preferably be folded again over itself and the bar, as above described; to make a more compact 45 parcel, nearly uniform in width, that will go into a smaller carton or box for shipping. In the operation, of the modified form, the contents may be expelled in the same way as in Fig. 2, by simply flattening the side wall

14 against the bar; or by twisting as at 15, 50 the sealed end 11 and loop B' inside; while the tubular portion is firmly held, and gradually collapsed, by the twist, progressing toward the other end 12.

While I have shown the portion E of the bar, nearest the sealed end of the tube, as being broadened to nearly the width of the tube itself, as a better holding or handling means; still a reinforcing bar of uniform breadth, or approximately so throughout its 60 length, and of relatively narrower width and thickness than illustrated, is all within the contemplation of this invention.

What I claim is:

1. A collapsible tube having a relatively 65 rigid reinforcing bar placed inside lengthwise thereof; whereby in using the device the tubular portion may be collapsed transversely, but not longitudinally of the bar to dispense the contents of the tube. 70

2. In a device of the character described, a collapsible tube and a relatively rigid reinforcing bar placed inside thereof centrally disposed and lengthwise of the tube; the end of the bar, nearest the sealed end of the 75 tube, being somewhat broad; whereby the wall of the tube may be collapsed upon the sides of the bar, to dispense the contents of the device; the device itself not being otherwise flexible lengthwise of the bar. 80

3. In a device of the character described, a collapsible tube, a relatively rigid reinforcing bar placed inside and centrally lengthwise thereof; the filling end of the tube being collapsed, sealed, and having its sharp 85 corners on opposite sides folded back upon the wall of the tube, thereby reducing the width of the tube at its sealed end, the wall of the tube being collapsible upon the sides of the bar, but otherwise practically inflexible lengthwise thereof. 90

In testimony whereof, I sign this specification in the presence of two witnesses.

LE VERT CLARK.
